UNITED STATES PATENT OFFICE

2,366,974

CHANGE-SPEED GEARING FOR MACHINE TOOLS

Arthur Harold Lloyd, Coventry, England, assignor to Alfred Herbert Limited, Edgwick, Coventry, England

Application November 20, 1942, Serial No. 466,340
In Great Britain October 29, 1941

2 Claims. (Cl. 60—97)

This invention relates to lathes or other machine-tools, our main object being to provide an improved pre-selective change-speed gearing therefor which in some conditions can advantageously be used instead of the "preemptive" gearings described in British patent specifications Nos. 382,784, 429,741, 434,893, 441,141, 446,772 and 466,789 in the names of Alfred Herbert Limited and another or others.

More particularly the invention relates to a change-speed gearing of the kind which includes a plurality of gear pairs which can be entrained, respectively, by slideable members (for example friction clutches, dog clutches or slideable gears).

A particular object of the invention is to arrange for the slideable members to be selectively movable by hydraulic mechanisms, on the actuation of a master valve controlled by a pilot valve, dependently upon the setting of a selector valve means which carries the fluid pressure only while the slideable members are being actuated and which at other times is free to be pre-set.

A further object is to arrange that the slideable members are operable by striking forks parts of which are grouped together, the said grouped parts being selectively movable by hydraulic mechanisms, which are correspondingly grouped, dependently upon the setting of a selector valve means.

These and other objects and advantages of the invention will best be understood if attention be directed to the following description in which reference is made to the accompanying sheets of diagrammatic drawings, wherein—

Figure 1 is a plan of a lathe headstock according to the invention, with part of the casing broken away to disclose the hydraulic means, the gearing and the striking forks therefor being omitted;

Figure 2 is an end elevation of the headstock with part of the casing broken away to disclose the striker forks and the coacting hydraulically-acting pinions by which they are actuated, the hydraulic mechanisms being omitted in this case;

Figure 3 is a developed view of the gearing;

Figure 4 is a sectional elevational view to a larger scale through the hydraulic mechanisms, the section being taken mainly on the line IV—IV of Figure 5 but the pilot valve being omitted;

Figure 5 is a sectional plan to the same scale of the hydraulic mechanisms;

Figures 6 to 10 are fragmentary sectional views, similar to that of Figure 4, taken on the lines 55

VI—VI, VII—VII, VIII—VIII, IX—IX and X—X of Figure 5, respectively;

Figures 11 and 12 are developed views of the rotatable sleeve and the stationary sleeve, respectively, of the selector valve means; and

Figure 13 is a developed view of another form of change-speed gearing which could be operated by the hydraulic mechanisms of Figures 4 and 12.

In Figures 1 to 3, 11 represents the input shaft 10 and 12 the spindle. On the input shaft is a sleeve 13 fast with different-sized gears 14, 15 which are respectively meshed with gears 16, 17. A clutch 18 is provided for connecting the sleeve 13 to the input shaft or for freeing it when desired. Coacting with the gears 16, 17, which are free on the shaft 19, are multi-plate clutches selectively operable by the sliding movement of a slideable member in the form of a control collar 20. Fast on the shaft 19 are different-sized gears 21, 22 which are respectively meshed with gears 23, 24 free on a shaft 25. Associated with the gears 23, 24 are multi-plate clutches which can be selectively engaged by means of a slideable collar 26. Thus, by selective positioning of the slideable collars 20, 26 four different speeds can be obtained on the shaft 25.

The latter shaft is connected in a similar way with a shaft 27 by gear pairs 28 and 29 which can be selectively entrained through multi-plate clutches by operation of a sliding collar 30. The drive from the shaft 27 to the spindle 12 is by the gear pair 31, and it will be observed that the gearing thus provides a choice of eight different speeds at the spindle.

In the present instance the three slideable members 20, 26, and 30 are grooved and engaged by striking forks 31, 32, and 33 respectively, and each of the striking forks is formed with a glut 34 (Figure 4) which is supported on a bar 35, the gluts being grouped beside one another, as shown most clearly in Figure 2. Each glut is formed with rack teeth 36 engaged with a pinion 37 which is disposed beneath it. On opposite sides of each pinion are disposed hydraulic devices, each pair of devices comprising plungers 38, 39 working in cylinder bores, the upper ends of the plungers having secured to them rack plates 41 engaged with the pinion. In Figure 5 the cylinder bores associated with the striker fork 31 are marked 42, those for the striker fork 32 are marked 43, and those for the other striker fork 44.

Disposed beneath the pinions in the casing 49 of the hydraulic mechanism is the rotary element 50 of a selector valve means which in the present instance is an 8-position element. The rotary

element 50 is fast with a sleeve 50a for convenience of manufacture, and the latter sleeve turns in a sleeve 49a fast with the casing 49, the two sleeves being secured, respectively, by grub screws 53. The rotary element 50 and sleeve 50a can be turned by a spindle 51 carrying at the front of the headstock a handwheel 52 for setting or pre-selection purposes.

The supply of the fluid pressure to the selector valve means is controlled by a master valve and a pilot valve, and when the master valve is in operation it provides a complete seal, thus leaving the selector valve means free of fluid pressure so that the rotary element may be pre-set as desired.

In the drawings (Figure 5) the master valve includes a casing 59 in which is a ball 60 and a plunger element 61. Fluid at an appropriate pressure is supplied through the inlet 62, tending to unseat the ball, but the same fluid pressure passes by the passage 63 through the port 64 and the port 65 to the underside of the plunger element 61, which therefore holds the ball 60 in the sealing position by the pressure difference.

The pilot valve includes a waisted plunger 66 which in the position shown in Figure 5 places the ports 64, 65 in communication with one another. It is biased downwardly by a spring 67 to the position shown, and it carries an operating stem 68 which extends to the front of the headstock.

Having pre-set the selector valve means—for example, to the position shown by Figures 4 to 10—when the new speed is to be introduced the operating stem 68 of the pilot valve is depressed by the operator in charge of the machine, and when the lower collar 70 on the plunger 66 has passed the port 65 the pressure in the space 71 below the plunger element 61 is placed by way of the port 65 in communication with the exhaust passage 72 and the supply of pressure through the port 64 is, of course, cut off. In these conditions the pressure on the ball 60 unseats the ball and the pressure then passes by way of the passages 74 to one of the ports 75 in the rotary sleeve 50a and to the peripheral groove 76 in the rotary element 50. The groove 76 communicates with longitudinal passages 77 in the rotary element which terminate at the peripheral groove 78 near the other end of the rotary element. Thus, fluid under pressure is supplied from the groove 78, through the port 79 in the rotary sleeve 50a (Figures 5 and 6), through the port 80 in the fixed sleeve 49a, to the passage 81 leading to the underside of the left-hand plunger (38) of the cylinder pair 44. It will be seen from Figures 5 and 8 that fluid under pressure is also being supplied from the groove 82 in the rotary element 50 through the ports 83 to the passage 84 leading to the underside of the left-hand plunger (38a) of the cylinder pair 43. From Figures 5 and 10 it is apparent that the pressure is being supplied from the groove 85 in the rotary element 50 to the ports 86 and thence by the passage 87 to the underside of the right-hand plunger (39) of the cylinder pair 44 is placed in communication with the exhaust passage 88 extending along the rotary element 50 by way of the passage 89, the ports 90, the peripheral groove 91, and the port 92—see Figure 4. The underside of the right-hand plunger (39a) of the cylinder pair 43 is exhausted through the passage 93, ports 94, and passage 95—see Figure 7, while the underside of the left-hand plunger (38b) of the cylinder

pair 42 exhausts through the passage 96, the ports 97, and the passage 98. Thus the striker forks 32 and 33 are moved in the same direction—to the right in Figure 3—and the striker fork 31 in the opposite direction.

It will be obvious that for another setting of the rotary element 50 and associated sleeve 50a the fluid pressure would be applied (on the operation of the pilot valve) to the underside of the plunger 39, the underside of the plunger 38 being placed in communication with the exhaust, in which case the glut 34 of Figure 4 would be slid to the right. In a similar way, for any setting of the rotary element of the selector valve means the other two pairs of cylinders above the bottom pair in Figure 5 are similarly selectively placed in communication with the pressure and exhaust respectively dependently upon the setting of the selector valve means. The necessary passages and ports are shown in the drawings and their arrangement will be clear to those skilled in the art, and it is not believed that further description will be necessary.

Figure 11 represents the layout of the ports in the rotary sleeve 50a, and the dotted lines represent the grooves and holes in the rotary element 50. Figure 12 refers to the stationary sleeve 49a. The ports marked L in Figure 12 are associated with the left-hand cylinders and those marked R with the right-hand cylinders.

The change of speed can take place almost instantaneously, so that it is unnecessary for the operator to hold the pilot valve operated, and on release of the stem 68 the parts return to the position shown in Figure 5 when the differential pressure acting upon the plunger element 61 will again close the master valve 60, thus leaving the selector valve means free to be re-set.

In the gearing of Figure 13 the input shaft 11a can drive the two gears 14a, 15a, and these can be selectively meshed with the twin gears 16a, 17a which are fast with a collar 20a slidable upon the shaft 19a. Fast on the latter are gears 21a, 22a which can be selectively meshed with the slidable twin gears 23a, 24a fast with a collar 26a. In a similar way the gear pairs 28a, 29a can be selectively entrained in the drive to the shaft 27a by movement of the slidable collar 30a, the final drive to the spindle 12a being by the gear pair 31a. Obviously the three slidable members 20a, 26a and 30a may be engaged by striker forks which are hydraulically actuated as described above in connection with Figures 1 to 12. In this case, however, the pilot valve must be held operated until the change has been effected, as there may be a slight delay in bringing the gears of a gear pair into mesh.

The fluid pressure may be generated, if desired, by a relatively-small constant-delivery pump (not shown) working in combination with an accumulator unit, and a by-pass system may be arranged whereby when the accumulator unit is fully charged the delivery from the pump will be transmitted to the headstock for lubrication purposes. For cooling purposes the accumulator unit or other portions of the hydraulic system may, if desired, be disposed away from the machine-tool, for example, on the floor adjacent the machine-tool.

By the use of an accumulator unit only a small pump is necessary, and quick operation of the clutches or slidable gears can be obtained. The push-button pilot valve provides a very light control.

What I claim as my invention and desire to secure by Letters Patent of the United States is:

1. A power unit comprising a shaft, gears on successive portions of the shaft, pairs of racks, each rack of a pair meshing with its respective shaft gear at substantially diametrically opposed points, hydraulic pistons carrying said racks, substantially vertical cylinders receiving said pistons, a valve chamber beneath said shaft and between the said cylinders ported to communicate with the lower portions of the cylinders, and a selector valve rotatably mounted in said chamber having inlet and exhaust channels and ported to register in various angular positions with the ports of the cylinders in prearranged sequence.

2. A power unit comprising a substantially horizontal shaft, pinions fixed on said shaft, rack pairs meshing respectively with diametrically opposite portions of said pinions and arranged to reciprocate substantially vertically, hydraulic plungers carrying said racks and disposed at opposite sides of said shaft, substantially vertical hydraulic cylinders for said plungers, a selector rotary valve disposed on a substantially horizontal axis below said shaft and between the lower por-

tions of said cylinders and having passages communicating with the lower portions of said cylinders, means whereby said selector valve may be manually set, a source of fluid pressure supply to said selector valve, a normally closed master valve between said source and the selector valve to normally remove pressure from the selector valve during setting, a pilot valve in communication with said source and in controllable connection with said master valve, said master valve having movable parts with opposed differential areas with the smaller area exposed to the pressure source, said pilot valve having ports to establish communication between the pressure source and the greater opposed area of said master valve, means for biasing said pilot valve to a position admitting source pressure to the larger area of said master valve to maintain said master valve normally closed, and means for shifting said pilot valve to cut-off the pressure source from the larger area of said master valve to permit automatic opening of said master valve and the flow of pressure to said selector valve.

ARTHUR H. LLOYD.
